US00D843967S

(12) **United States Design Patent** (10) **Patent No.:** **US D843,967 S**
(45) **Date of Patent:** **** Mar. 26, 2019**

(54) **COMMUNICATIONS HEADSET OR HEADPHONE**

(71) Applicant: **Plantronics, Inc.**, Santa Cruz, CA (US)

(72) Inventors: **Nicholas W Paterson**, Santa Cruz, CA (US); **Bowman Wang**, Ben Lomond, CA (US); **Gregor Magnusson**, Watsonville, CA (US)

(73) Assignee: **Plantronics, Inc.**, Santa Cruz, CA (US)

(**) Term: **15 Years**

(21) Appl. No.: **29/609,172**

(22) Filed: **Jun. 28, 2017**

Related U.S. Application Data

(63) Continuation-in-part of application No. 29/574,981, filed on Aug. 19, 2016, now Pat. No. Des. 813,837.

CLAIM

The ornamental design for a communications headset or headphone, as shown and described.

DESCRIPTION

FIG. 1 is a front-left perspective view of a communications headset or headphone showing my new design;

FIG. 2 is a back-right perspective view thereof;

FIG. 3 is a front view thereof;

FIG. 4 is a back view thereof;

FIG. 5 is a right side view thereof;

FIG. 6 is a left side view thereof;

FIG. 7 is a top view thereof; and,

FIG. 8 is a bottom view thereof.

The broken lines showing the unclaimed features form no part of the claimed design.

1 Claim, 8 Drawing Sheets
